ASH HANDLING DEVICE

William G. Uhler, Jr., Yeadon, Pa., assignor to
Ruth Kolb Uhler, Yeadon, Pa.

Application May 18, 1933, Serial No. 671,613

6 Claims. (Cl. 126—242)

This invention relates to ash handling devices, and has for an object to provide means attached to the heating unit, such for instance, as a domestic boiler, replacing the ash pit door, and forming an apron for the confinement of ashes from the ash pit to a receptacle located in a well or depression in the floor.

A further object of the invention is to provide a device hinged to the lower margin of the ash pit door opening, adapted to swing upwardly to close the opening, and with a member hinged to said swinging member, which will, in use, lie along the floor, said member provided with an opening registering with an underlying receptacle.

A further object of the invention is to provide a closure for an ash pit door, having a hinge, and a member hinged to said hinged member and adapted to fold simultaneously with the closing of the ash pit closure.

A further object of the invention is to provide a device which will be associated with an ash pit door providing in its own organization a closure for the door opening and a hinged extension, with an opening for registering with an underlying receptacle, both closure and extension being provided with upstanding flanges for restraining the ash in its course from the ash pit to the receptacle.

The invention, therefore, comprises a plate-like member which will combine with a furnace or other heating plant, in such manner as to close the ash pit door opening when swung to the upward position, and to form an outwardly extending apron when swung downwardly from closing position, with a second member hinged to the swinging member and provided with an opening for registering with an underlying receptacle, and with a flange carried by the extension member adapted to cooperate with the door closing member to form a passageway from the ash pit door to the receptacle wholly surrounded by an upstanding flange.

The drawings illustrate several embodiments of the invention and the views therein are as follows:

Figure 1 is a view in perspective of one embodiment of the invention shown in open position, adapted to conduct ashes from the pit door to a depressed receptacle.

Figure 2 is a view in edge elevation of the device swung to close the ash pit door.

Figure 3 is a sectional view through the device, showing its relation to the underlying well,

Figure 4 is a view in edge elevation of a slight-

ly different modification, shown in open position, and indicating its manner of closing the door, and

Figure 5 is a still different modification shown in edge elevation and in dotted lines in door closing position.

Like characters of reference indicate corresponding parts throughout the several views.

Heating plants, such for instance, as domestic types of boilers, are mounted in various ways. In some instances they are set above the floor level on a platform erected for the purpose and as indicated at 10 in Figures 1, 2, 3 and 4. These platforms may vary in height and in the drawings two different heights have been indicated. In other instances, the heating unit which will be referred to as a furnace 11, is set directly upon the floor level, as indicated in Figure 5.

In the application of the device to the furnace, the ash pit door is removed. The opening for the ash pit door is almost invariably surrounded by a bead 12 and a plate 13 is provided of such size as to close this opening. The plate is applied by means of clips 14 mounted upon opposite sides of the bead of the opening to which the plate is hinged. The plate is hinged in any approved manner, as by the rod 15 passing directly under the lower run of the bead 12.

As this plate 13 is thus hinged to a position under the bead, it will prevent the passage of ash between the bead and the plate. In the several types wherein the furnace is mounted upon a platform, as shown at 10, the plate will be inclined downwardly to the floor level, such inclination depending upon the height of the platform 10.

In the type shown at Figure 5 there is slight, if any, inclination. To the edge of the plate 13, which is outermost, a second plate 16 is hinged, as by the hinges 17, and is provided with an opening 18 of such dimension as to cooperate with a receptacle placed in an underlying well shown in Figure 3. Preferably, this opening 18 will be surrounded by a downturned flange 20 so that the flange, approximately fitting the underlying receptacle, will prevent the escape of ash.

The plate 13 is provided with a tongue 21 which, in extended position as shown at Figures 1 and 3, overlaps the edge of the plate 16, and thereby prevents the escape of ash.

About three sides of the plate 16 a flange is erected comprising the end flanges 22 and 23, and the side flange 24. The end flanges 22 and 23 are extended beyond the edge of the plate 16 opposite the flange 24. These extensions are shown at 25 and 26. The extensions 25 and 26 are provided with inturned flanges 27 and pref-

erably the ends of the plate 13 will be provided with upturned flanges 28. The two flanges 27 and 28 will, therefore, interlock to a certain degree to prevent the passage of ash under the 5 extensions 25 and 26.

In the type shown at Figures 1 to 4 inclusive, the ash pit opening is closed by merely raising the plate 13 with its hinge 17 traversing the dotted lines, as shown at Figures 3 and 4, until 10 it assumes the position shown at Figure 2 with the plate 16 extending at an inclination downwardly and may, in fact, serve as a means for holding the plate 13 in closed position over the opening.

15 When being raised along a path indicated by the dotted line, the side flanges 25 and 26 will move upwardly along the front of the furnace to the position shown at Figure 2.

In opening, the hinge 17 will traverse the dotted 20 lines shown at Figure 2 until the position shown at Figures 1, 3 and 4 has been attained.

In the type shown at Figure 5, the flanges 23' are hinged at 29, as is also the plate with the opening. Thus constructed, the hinge 17 may 25 move on the dotted line, as shown, and by retaining the hinge 29 at or about upon the floor level, the extension 25' will move upwardly to the position shown in dotted lines as 25".

The hinge 29 is made necessary for the reason 30 that the outwardly extending part must fold to the position shown in dotted lines, so that the flange 23', which is in this modification straight instead of bent, may extend upwardly along the furnace front, as indicated.

35 This type is operated exactly as the type shown in the other figures, and with the exception of the hinge formed in the side flanges 22' and 23', and the connecting plate, the construction and operation is identical.

40 Of course the ash handling device herein illustrated may be modified and changed in various ways without departing from the invention herein set forth and hereafter claimed.

The invention is hereby claimed as follows:

45 1. An ash handling device adapted to be associated with a furnace having an ash pit opening, comprising a plate provided with a hinge adapted for connection with the furnace and to underly the opening of the ash pit, a second plate hinged 50 to the first mentioned plate and provided with an opening therethrough for register with an underlying receptacle, and an upstanding flange embracing both of said plates.

55 2. An ash handling device, comprising a plate having a hinge along both edges, a second plate

hinged to the first mentioned plate at one of said hinges, said second plate being provided with an opening having a downturned flange, and a flange carried by the second mentioned plate extending over and cooperating with the edges of the first mentioned plate.

80 3. The combination with a furnace having in a vertical wall an ash pit opening surrounded by a bead, of a road fixed beneath the lowermost reach of the bead, a plate hinged to the rod and extending outwardly and proportioned to swing upwardly to close the opening, a second plate hinged to the edge of the first mentioned plate opposite its hinging to the furnace, said second mentioned plate being provided with an opening therethrough proportioned to cooperate with an underlying receptacle.

85 4. An ash handling device in combination with a furnace having an ash pit opening surrounded by a bead, said device comprising a rod fixed beneath the lower reach of the bead, a plate hinged to the rod and proportioned to swing upwardly to close the opening, a second plate hinged to the first mentioned plate and adapted to swing downwardly as the first mentioned plate swings upwardly, said second mentioned plate being provided with an opening therethrough proportioned to register with an underlying receptacle, and a flange surrounding the plates when in the extended positions.

90 5. In combination with a furnace having an ash pit opening surrounded by a bead, a plate hinged beneath the lowermost reach of the bead and adapted to swing upwardly to closing position over said opening and outwardly away from such closing position, a second plate hinged to the edge of the first mentioned plate opposite the hinging to the furnace, said second mentioned plate being provided with an ash discharge opening, and a flange carried by the second mentioned plate having extensions beyond the lines of said plate cooperating with the edges of the first mentioned plate.

95 6. The combination with a furnace having an ash pit opening surrounded by a bead, a plate hinged beneath the bead and adapted to swing upwardly to closing position over said opening and outwardly away from closing position, a second plate hinged to the first mentioned plate, flanges upstanding from the second mentioned plate and extending over and cooperating with the edges of the first mentioned plate, said second mentioned plate and flanges thereon being hinged to form coacting sections.
